[57] CLAIM

The ornamental design for a temperature measuring housing, as shown and described.

DESCRIPTION

FIG. 1 is a front view;

FIG. 2 is a bottom view;

FIG. 3 is a top view;

FIG. 4 is a left side view;

FIG. 5 is a right side view;

FIG. 6 is a back view;

FIG. 7 is a perspective front view from the bottom left;

FIG. 8 is a first alternative embodiment of FIG. 1; and,

FIG. 9 is a second alternative embodiment of FIG. 1.

The remaining views of FIGS. 8 and 9 are identical to those views shown in FIGS. 2-6.

FIG. 3

FIG. 4

FIG. 5

FIG. 2

FIG. 6

FIG. 7

FIG. 8

FIG. 9
